UNITED STATES PATENT OFFICE.

RICHARD CLEARY, OF BINGHAMTON, NEW YORK.

VEGETABLE AND FRUIT SLICER.

Application filed December 20, 1924. Serial No. 757,295.

My invention relates to vegetable and fruit slicers or cutters, and it has for its object to provide a slicer for vegetables, or fruit, whereby a plurality of slices or cuttings may be made at one movement of the instrument; with these objects in view my invention consists in certain novel features of construction and arrangement of parts as are more particularly described and pointed out in the claims, reference being had to the accompanying drawings, in which:

Fig. 1 is a perspective view of my device in closed position.

Fig. 2 is a side view of my device in open position.

Fig. 3 is an end view of my device in closed position.

Fig. 4 is a fragmentary end view of part of my device.

Fig. 5 is a fragmentary end view of part of my device.

The same reference characters denote like parts in each of the several figures of the drawings. In carrying out my invention, I provide a cutting block A in which may be provided on its upper surface a series of grooves and on either side at one end thereof are provided pivot lugs B. Mounted on the cutting block A I have the knife holder frame C provided with handle D. Supported in the frame C are the knives 2 each knife having projecting from the upper surface thereof at one end the lugs 3 and at the other end the lugs 3', each having respective recesses 4 and 4'. The frame C consists of the side bars 5 and end bars 6 and 6', the end bar 6 having slots or recesses 7 and the end bar 6' having the recesses 7', the lugs 3 engaging the recesses 7 and the lugs 3' engaging the recesses 7'. As shown in the drawing, wedge blocks 9 are provided for engaging the lugs 3' for holding the cutters in position in the frame, each wedge block engaging two of the cutters and being secured to the frame C by set screws 10.

The end bars 6 of the frame C may have

down turned ears 12 having the pintles 13 for engaging hooks 14 of the lugs B, the pintles being first normally upwardly 50 against the lower surface 15 of the hooks 14 by means of suitable springs 13.

In the operation of my device when I desire to slice vegetables or other material by grasping the handle D and lifting the cutter frame C, I raise the knives from the block surface and place on the block A the object to be cut, and bearing down on handle D, a plurality of parallel uniform cuttings are made, forming elongated slices, from the object cut. By again turning the slices across the block, and again cutting a plurality of short slices are formed, and in this manner, by changing the position of the material, a variety of sizes and forms of 60 cuttings are made. My device is especially adapted for slicing vegetables in various forms for cooking and table use.

Having thus described my invention what I claim as new and for which I desire Letters Patent is as follows:

1. In a vegetable slicer a cutting block, pivot supports mounted at either end of the cutting block, a cutter frame, a pair of pivot pins carried by the cutter frame and pivotally supported in the pivot supports, springs for exerting a yielding pressure upwardly against the pivot pins, and a plurality of knives removably mounted on the cutter frame, and means for securing the knives in operative position.

2. In a slicer the combination with a cutting block of a knife frame pivotally supported thereby, a plurality of cutting knives removably mounted in the frame each cutting knife being provided with lugs for engaging with recesses in the frame at either end and wedge blocks engaging the lugs at one end for securing the knives in operative position.

In testimony whereof I have affixed my signature.

RICHARD CLEARY.
